DECORATIVE HIDDEN HOOK

Carolyn L. Johnsen and Walter J. Johnsen, both of 921
Kirby Drive, La Habra, Calif. 90631

Filed Dec. 26, 1973, Ser. No. 428,357

Term of patent 3½ years

Int. Cl. D8—08

U.S. Cl. D8—257

FIG. 1 is a front elevation view of a decorative hidden hook showing our new design;

FIG. 2 is a left side elevation view thereof; and

FIG. 3 is a rear elevation view thereof.

We claim:

The ornamental design for a decorative hidden hook, as shown.
